Primary Examiner — Dominic Simone(74) Attorney, Agent, or Firm — Terence P. O'Brien(57) CLAIM

I claim the ornamental design for a lower portion of a footwear article, as shown and described.

DESCRIPTIONFIG. 1 is an upper, side perspective view of a lower portion of a footwear article; and,
FIG. 2 is a side elevation view of the lower portion of the footwear article of FIG. 1.

The ornamental design that is claimed is shown in solid lines in the drawings. The broken (dashed) lines shown in FIGS. 1 through 2 are included for the purpose of illustrating environmental elements only and form no part of the claimed design.
